Frank Freeman

UNITED STATES PATENT OFFICE.

WILLIAM H. ROSE, OF JERSEY CITY, NEW JERSEY, ASSIGNOR OF ONE-HALF TO
HOWARD S. NEIMAN, OF NEW YORK, N. Y.

PHONOGRAPH RECORD.

Application filed April 16, 1920. Serial No. 374,257.

To all whom it may concern:

Be it known that I, WILLIAM H. ROSE, a citizen of the United States, residing in Jersey City, county of Hudson, and State of New Jersey, have invented certain new and useful Improvements in Phonograph Records, of which the following is a full, clear, and exact specification.

My invention relates to phonographic records and refers particularly to records known commercially as disc records.

The ordinary disc record comprises a flat disc carrying sound wave impressions capable of being converted into sound waves by means of the usually employed sound producing mechanisms of a phonograph.

The practical methods of producing, duplicating and using the disc records necessitate a limitation to their size, usually to 12 inches in diameter, and as the period of time required for the sound reproduction of a record is governed by the length of the sound wave recording groove, it is evident that the duration of a reproduction from the present known records is limited to the length of a sound record capable of being impressed upon a flat surface of the area of the record.

There are certain physical reasons necessitating a blank, or un-recording surface, upon portions of the record, thus causing a further limitation to the record area capable of sound reproduction.

The standard phonographs are so constructed that imperfect, or no, sound reproductions can be obtained from a record having a diameter of greater than 12 inches.

The device of my invention allows a very considerably longer sound reproduction with regard to a time period, than can be obtained from a flat disc record of the same diameter and this increase is obtained without a diminution of sound perfection.

My device further allows the standard phonographs to reproduce a longer sound record than they can reproduce from any other known record.

The device of my invention is, therefore, a new, novel and useful phonograph record, producing results unobtainable from a flat disc record.

One form of the device of my invention is shown in the accompanying drawings, in

which similar parts are designated by similar numerals:—

Figure 1 represents a top plan view of one form of a device of my invention.

Figure 2 represents a section through the line 2—2 of Figure 1.

Figure 3 is an enlarged fragmentary detail section of the record showing the sound wave impressions.

The particular form of my device, shown in the accompanying drawings, comprises a disc 10, having a central opening, or hole, 11, into which a pin of a revoluble phonograph table may be inserted in the ordinary manner to retain the disc in position upon the table. A portion of the disc 10 carries a series of concentric undulations 12, 12, 70 thus giving that portion of the surface of the disc 10 an undulated, or waved, effect. The outer portion 13 of the disc 10 may be flat as indicated. The disc 10 carries an outer annular flange member 14. A surface 75 of the disc 10 has a groove 15, carrying sound wave impressions capable of conversion into sound waves in the ordinary manner by means of a phonograph. This groove is spiral in formation, may be of the desired 80 length for sound reproduction and may be upon either or both sides of the disc.

It is evident that the length of a sound wave impression groove, capable of being carried by an undulated disc, is greater 85 than that capable of being carried by a flat disc of the same diameter, on account of the greater surface area of the former.

The use of my device, therefore, enables the production of a much longer sound record upon a disc of given diameter than can be obtained otherwise, and hence, the effective capacity of the standard phonograph is materially increased.

I do not limit myself to the particular 95 size, shape, number or arrangement of parts as shown and described, all of which may be varied without going beyond the scope of my invention as shown, described and claimed.

What I claim is:—

1. A single continuous disc phonograph record having a series of concentric undulations carrying sound wave impressions capable of reproduction into sound waves. 105

2. A single continuous disc phonograph

record having a series of concentric undulations within which is a continuous spiral undulating groove carrying sound wave impressions therein capable of reproduction 5 into sound waves.

3. A phonograph record having a series of uniform concentric undulations carrying

sound wave impressions capable of reproduction into sound waves.

Signed at New York city, in the county ¹⁰ of New York and State of New York this 14th day of April, 1920.

WILLIAM H. ROSE.
